SAVINGS DEVICE

Herman Albert Binder, San Francisco, Calif.

Application June 17, 1933, Serial No. 676,258

3 Claims. (Cl. 232—4)

My invention relates generally to coin saving devices, and more particularly to display devices equipped with coin receiving means.

It has been common practice by such institutions as banks and other institutions interested in the encouragement of thrift and savings, to employ various schemes, devices and the like to further this end. For example, such associations have distributed among their customers various types of coin receiving banks for the purpose of encouraging consistent savings. Unless the device designed to receive the coin is arranged so as to render the same conveniently and quickly accessible each time a deposit is to be made, a consistent savings program fails to be encouraged thereby. It is with the thought in mind of providing a coin receiving device or savings bank, which is constructed and arranged to foster and sustain the savings idea on the part of the user that I have made the present invention. In fact, it is one of the primary objects of my present invention to provide a simple, unique, and attractive savings device of the easel type, which is always conveniently accessible and which, because of its very nature or form, is frequently observed by the user.

In accordance with the foregoing object, I propose to provide a device including a panel and a support member connected therewith for retaining the panel in proper display position in combination with a coin receiving receptacle or bank adapted to be supported by said elements in a convenient and accessible position for receiving coins.

More specifically, my invention contemplates a device as above set forth, in which the coin receiving receptacle is so positioned when the panel occupies a display position, that a restricted opening provided at the upper portion of the receptacle is conveniently located for receiving coins and currency.

Another object of my invention is to provide in an easel device of the type mentioned above, a coin receptacle or bank which is supported thereby and which is positioned at the rear side of the panel, thereby rendering the receptacle proper inconspicuous to the eye of an observer, and at the same time accessible for receiving coins.

A further object of my invention is to provide an easel device of the type mentioned wherein means is provided in association with the coin receptacle or chamber to permit the convenient withdrawal of accumulated coins from one end thereof.

Still more specifically, my invention contem-

plates an easel device, in which the support member hingedly connected with the panel or frame is formed with a chamber having an opening for receiving coins at the upper portion of the hinged member.

The foregoing and numerous other objects and advantages will be more apparent from the following detailed description when considered in connection with the accompanying drawings, wherein—

Figure 1 is a perspective view of the rear side of an easel device embodying features of my invention;

Figure 2 is a front elevational view of the device shown in Figure 1;

Figure 3 is an enlarged vertical sectional view of the hinged support member, said view being taken substantially along the line 3—3 of Figure 1;

Figure 4 is a perspective view of the rear side of a modified savings device, which is also an embodiment of my invention;

Figure 5 is an enlarged fragmentary transverse sectional view of the lower portion of one of the hinged support members of Figure 4;

Figure 6 is a fragmentary vertical sectional view of the lower portion of a support member equipped with a modified coin releasing device;

Figure 7 is a view similar to Figure 6, disclosing a modified key controlled closing device 30 for the coin receptacle;

Figure 8 is still another modified construction whereby the removal of the accumulated coins may be conveniently accomplished;

Figure 9 is a front elevational view of a modified savings device provided in the supporting base of a pivoted or swinging stand frame;

Figure 10 is a perspective view of the rear side of the lower portion of the device shown in Figure 9;

Figure 11 is a vertical transverse sectional view of the supporting base taken substantially along the line 11—11 of Figure 10; and

Figure 12 is a transverse sectional view taken substantially along the line 12—12 of Figure 11.

Referring now to the drawings more in detail wherein like numerals have been employed to designate similar parts throughout the various figures, it will be seen that my invention contemplates the provision of a savings device, as shown in Figures 1 to 3, inclusive, which includes a panel member or section designated generally by the numeral 10, and a support member therefor designated generally by the numeral 12. In the drawings I have shown the panel 10 as including

a frame section 14 and a panel section or back 16, to which the support member 12 is secured by means of a suitable flap or hinge 18. I make reference to the part to which the support member 5 12 is connected as a panel, and in using the term "panel", I include either a single plaque or a plaque and frame construction of the type shown in the drawings.

The support member or section 12 serves the 10 double function of supporting the panel 10 and also a coin receiving device or receptacle 20, which actually forms a part of the support member. The upper portion of the receptacle 10 is provided with a restricted coin receiving aperture or slot 22, 15 while the lower end of the receptacle is provided with a removable closure member 24, which is adapted to be withdrawn by exerting a pull on a ring 26. The withdrawal of a closure member 24 permits of the convenient removal of accumulated coins. To limit the outward swinging of the 20 support member, I provide the usual flexible strip 28, Figure 1.

In Figures 1 to 3, inclusive, I have shown the panel as not only including the back 16 and the 25 frame 14, but also a front glass section 30. Beneath the glass I propose to display any desired object. For purposes of illustration I have indicated a document 32, which I have designated as a life insurance policy. To one side of the policy 30 I provide sufficient space for a letter to be written. This life insurance policy and the space adjacent thereto have been shown merely to illustrate one practical application of my invention. It will be apparent that by having the policy in 35 plain view of the owner and in proximity to the bank or receptacle 20, it will serve as a reminder of the savings program which must be consistently practiced in order to be in a position to pay for the premiums which come due from time to time. 40 Obviously other attractive displays may be carried by the panel, which will serve the same purpose as the policy. For example, the picture of a child or other member of the family could be substituted for the above mentioned policy. While 45 the life insurance policy, picture or other display member does not form a part of the invention per se, it does serve to indicate the practical significance of having my improved easel device equipped with the savings bank feature.

50 Referring to Figure 1, it will be seen that I provide a pair of coin receiving openings 23 at the back and toward the upper portion of the panel section 16. These openings communicate with companion chambers housed within the back 16, the lower ends of which terminate opposite the closure members or flaps 25. By opening the flaps 25, accumulated coins received through openings 23 may be removed. Thus I provide in the frame structure a pair of coin receiving receptacles, wherein individual deposits may be made. Obviously other forms of closure members may be made without departing from the spirit and scope of my invention.

In Figures 6 to 8, inclusive, I have disclosed 65 modified means for closing the lower end of the receptacle 20. Thus in Figure 6 a simple slide element designated generally by the numeral 24a is shown, which may be withdrawn in the same manner as the member 24 shown in Figure 1. 70 In Figure 7 a member 24b is disclosed which may be removed when a key controlled lock 34 is manipulated so as to release the member 36 from the member 38. In Figure 8 a still further modified closure member 24c is shown. This member 75 may be withdrawn from the bottom of the re-

ceptacle by merely depressing buttons 40 so as to release locking detents 42 from each end of the walls of the closure member 24c. It will, therefore, be apparent that the invention is not limited to any particular type of closure member, 5 but contemplates various modifications without departing from the spirit and scope thereof.

In Figures 4 and 5 a modified support member is shown which I have designated generally by the numeral 12a. One of these support members or sections 12a is mounted at each side of the panel 10 and is secured to the panel by suitable hinge members or flaps. The upper end of a receptacle 20a which actually forms a part of the support member 12a is provided with a restricted opening or slot 22a for receiving coins. The lower extremity of each of the support members 12a is provided with a closure member 24d, which, like the closure member 24b of Figure 7, is equipped with a key controlled lock 34d. By 20 turning the lock 34d, a member 36d is released from a locking element 38d so as to permit the convenient withdrawal of the closure member 24d.

The support members 12 and 12a have surfaces 25 designed to receive tables and the like, which indicate the manner in which small savings, if consistently made, will eventually amount to a considerable sum. In other words, my invention contemplates the provision of support members, a surface of which is designed to receive and conveniently display instructions or indicia. It will be apparent that when the savings device is positioned so as to properly locate the panel 10 for display purposes, any printing or writing thereon 30 will be hidden from the observer standing in front 35 of the device. Thus, my invention contemplates the provision of a savings device which is attractive, simple in construction, and extremely practical in use.

In Figures 9 to 12, inclusive, I have disclosed a 40 modified savings device in combination with the structure of a pivoted or swinging stand frame. The frame or panel is indicated generally by the numeral 10e and is pivotally supported at opposite sides by the upwardly extending members 46 45 of a support device which is indicated generally by the numeral 20e. This device 20e performs the same function as the members or devices 20 and 20a previously described inasmuch as it provides the support for the panel 10e. A base 48 50 provides a pair of elongated chambers 50, Figures 11 and 12, which are separated by a central partition 51 and adapted to receive coins inserted through slits or openings 52 companion thereto provided in the rear wall of the base 48. Having 55 the openings 52 thus positioned, they are rendered very inconspicuous to one observing the subject matter contained on the front side of the panel 10e. Slidably mounted within the bottom portion of the base 48 is a pair of closure members 54 which, when completely inserted within the base as shown in Figure 11 cover companion openings 56 provided within the bottom of the base. The closure members 54 may be pulled outwardly by merely gripping the flexible members 58 secured to the outer ends thereof. Obviously 60 the invention is not limited to the particular type of closure member shown in the drawings, but contemplates various forms of devices which will facilitate the removal of accumulated coins from the chambers 50. In Figure 10 I have shown in dotted lines the position occupied by the closure members when they have been pulled outwardly 65 so as to uncover the opening 56. It will be apparent that in the structures shown in Figures 9 70 75

to 12, inclusive, the supporting device 20e, which includes the base 48 and the upright members 46, serves the dual purpose of housing a savings bank and supporting a panel frame member 10e.

5 From the foregoing it will be observed that my invention contemplates the provision of coin and currency saving device of practical and simple construction, which serves to materially encourage thrift. The savings receptacle always occupies an inconspicuous, yet convenient position 10 for receiving monies. The savings receptacle being operatively associated with a frame or panel support permits attractive display, as well as photographs and the like, to be placed in juxtaposition 15 with respect thereto, so that the observer is constantly aware of the presence of the savings receptacle.

Obviously modifications and changes in structural design may be made without departing from 20 the spirit and scope of my invention.

Having thus described my invention, what I claim as new and desire to secure by Letters Patent is:

1. A savings device comprising a panel, a hinge 25 on the back of said panel, a substantially rigid coin box having a flat top with a coin slot therein and a flat bottom having a coin removing aperture therein, said box being pivoted at its top to said panel by said hinge, an openable closure for said aperture, and a strap connecting said box and said panel at a point away from said hinge and allowing said box to be pivoted away from 30 said panel on said hinge to define a selected angle with said panel.

35 2. A savings device comprising a panel, a hinge

on the back of said panel, a coin box having a flat top with a coin slot therein and a flat bottom and being pivoted at its top to said panel by said hinge, and a strap between said box and said panel at a point removed from said hinge and 5 limiting the movement of said box away from said panel, the lower back edge of said box extending to a point approximately even with the bottom of said panel and the front of said box being shorter than the back thereof and having 10 its edge above the lower edge of said panel when the box is parallel with said panel, whereby the bottom of said box lies flat on a supporting surface when said box is pivoted away from said panel to the full extent allowed by said strap. 15

3. A savings device comprising a frame, a panel within said frame, said frame and panel being adapted for receiving and displaying pictorial or reading matter, a hinge at the back of said panel, a support connected at its top to said panel by 20 said hinge, said support comprising a rigid box having a flat top with a slot therein near the side thereof away from said hinge and adapted to receive coins, a flat bottom having an aperture 25 adapted to allow removal of coins, and an openable closure for said aperture, said bottom being slanted upward toward said panel, and a strap connecting said box and said panel at a point away from said hinge and allowing said box to be pivoted on said hinge to describe a selected 30 angle with said panel, the bottom of said box being adapted to lie flat upon a supporting surface when said box is rotated away from said panel to the limit of said strap.

HERMAN ALBERT BINDER. 35
